UNITED STATES PATENT OFFICE.

WILLIAM C. PINSON, OF PINE BLUFF, ARKANSAS.

COTTON-PRESS.

SPECIFICATION forming part of Letters Patent No. 309,090, dated December 9, 1884.

Application filed June 7, 1884. (No model.)

To all whom it may concern:

Be it known that I, WILLIAM C. PINSON, a citizen of the United States, residing at Pine Bluff, in the county of Jefferson and State of Arkansas, have invented a new and useful 5 Cotton-Press, of which the following is a specification, reference being had to the accompanying drawings.

This invention has relation to cotton-presses, 10 and it has for its object to produce a cotton-press that shall possess superior advantages in point of simplicity, durability, and general efficiency over others of its class; and it consists in the construction and novel arrangement of parts, as will be hereinafter fully described, and particularly pointed out in the 15 claim.

In the drawings, Figure 1 is a view in perspective of a cotton-press embodying my improvements. Fig. 2 is a vertical longitudinal sectional view, and Fig. 3 is a detail view showing a portion of the bale-chamber with the sliding top block partly withdrawn.

Referring by letter to the accompanying 25 drawings, A designates the frame of the press, which is made of strong timber suitably braced. The press is an upright press, and the follower works from below upward through the cotton-box. The beams B B, that support 30 the windlass C, are sustained by suitable supports, and are connected by cross-pieces D D at some distance from the ends of said beams B B. The upper ends of the guides E E for the cross-head of the follower-rods are mortised 35 into these cross-pieces D D, the lower ends of said guides E E being mortised into a sill, F, which rests on the ground or floor of the press-house.

G designates the cotton-box, and H the bale-chamber. The follower I is connected to the 40 upper ends of the follower-rods J J through lugs K K on its under side. The lower ends of the follower-rods J J are rigidly secured in a cross-head, L, having guide-irons M at each 45 end, which engage the guides E E. The cross-head L is provided, between the lower ends of the follower-rods J J, with an iron pulley, N. A cross rod or bar, O, is secured in the beams B B beneath the windlass C, and to this cross-

bar O one end of the rope P, that operates the 50 follower-rods and follower, is secured. This rope P passes down around the pulley N and up to and is secured at its other end to the windlass C. The windlass-shaft Q is provided with a wheel, R, to which the power is applied 55 to operate the cotton-press. The top block, S, is provided on its under face with transverse strips having spaces between them, and the follower is grooved in its upper face. The top block, S, slides in horizontal guides T at 60 the upper end of the bale-chamber, so that it is only necessary to slide it to one side to feed the cotton to the press. The bales are tied while in the bale-chamber, and are removed 65 therefrom in the usual manner.

This cotton-press operates to compress the bale by winding the rope upon the windlass, which causes the follower to move up in the cotton-box and to compress the cotton in the bale-chamber. After the bale has been formed, tied, and removed, the windlass is reversed, 70 the rope unwinds, and the follower recedes by its own gravity to the bottom of the press-box, and the operation is repeated for the next bale.

This cotton-press is cheap and simple in its 75 construction, and is not likely to get out of order; but if it should need repairs from long use it can be repaired by any person possessing ordinary skill.

Having thus fully described my invention, 80 what I claim as new, and desire to secure by Letters Patent of the United States, is—

The combination, with the press-frame provided with the cotton-box, bale-chamber, and top block, of the guide-rods E E below the 85 cotton-box, the follower I, the follower-rods J J, and cross-head L at their lower ends, provided with the iron pulley N, the guide-irons M M, the cross-bar Q below the windlass, and the rope P and windlass C between the follower-rods J J, substantially as specified.

In testimony that I claim the foregoing as my own I have hereto affixed my signature in presence of two witnesses.

WILLIAM C. PINSON.
